GRINDING MILL

John Mursch, Teaneck, N. J.

Application December 23, 1935, Serial No. 55,687

5 Claims. (Cl. 83—11)

This invention relates to a grinding mill of the type using rotating hammers where either the hammers themselves or the links carrying at their outer extremities the separate hammer ends are swingingly or pivotally mounted upon the carrying disks or other carrying members.

In these grinding mills it has heretofore been common to swingingly mount elongated hammers or to swingingly mount the hammer assemblies so that if a hammer strikes an obstruction in the mill, the hammer or the hammer assemblies may swing backward to relieve the tension and to allow the hammer to pass the obstacle without damaging the machine. It has been recognized, however, that these swingingly carried hammers have several serious disadvantages in practice. One disadvantage is that when a hammer or a hammer carrying link has been swung back from its usual radiating position, due to meeting a greater obstacle than usual, this deflection of the hammer puts all of the rapidly rotating mechanism of the grinding mill out of balance through there being temporarily more weight and more centrifugal force on one side of the shaft than on the other with a resulting strain and consequent vibration in the machine. Another disadvantage of the independently mounted swingingly supported hammers or hammer links is that when the machine is stopped, all of the hammers swing downwardly on their pivots due to the weight of the hammers. This swinging of all the hammers to one side continues for an appreciable space of time after the machine is placed in motion and during such displacement the rotating parts of the grinding mill are obviously in badly unbalanced condition actually by weight and also as to centrifugal tension. This out-of-balance condition as the machine is being gotten under headway continues until the rotating parts have acquired momentum sufficient to cause the centrifugal force so generated to bring the swingingly mounted hammers out to a radiating position. This general out-of-balance condition of all of the swinging hammers which occurs when the machine has been stopped and is being started puts a serious strain and vibration upon the machine and I have found also greatly adds to the starting load upon the electric motor or other motive power as compared to the normal operation of the machine and even as compared to the power required to start a machine where the hammers are in balanced condition from the very beginning of the rotation of the hammers and all the rest of the rotor.

A still further disadvantage, inherent in the independent swingingly mounted hammers and hammer assemblies is that to avoid noise, waste of power, vibration and the bodily unbalancing of the machine through the hammers dropping by gravity when the machine is driven too slowly,

it has heretofore been impracticable to slowly operate a grinding mill of the type indicated. In grinding many materials it is highly desirable not to have the hammers strike the material with the force and speed at which a grinding mill of the swingingly mounted hammer type must be operated. In fact, to avoid damaging material and sometimes to avoid setting fire to, or exploding material, it is imperative to keep the grinding members from striking the material so fast or with such speed.

It is the main purpose of my present invention to overcome the several disadvantages above mentioned and to provide a grinding mill of the swinging hammer type wherein the swinging hammers of a pair or series of hammers are automatically counterbalanced by means co-operatively connecting the hammers of said pair or series of hammers so that when one hammer is deflected, its co-operating member or members will be correspondingly and proportionately deflected so that said pair or series will not be out of balance whether the machine is stopped or in rapid or slow motion, and further so that when the machine is stopped all of the hammers of a pair or series of hammers in the machine will be in balanced condition and the hammers of the different pairs or series and the hammers of all of the series in a machine will be in balance. In other words, one purpose of this invention is to so co-operatively connect the swinging hammers of a pair or series of hammers as to at all times hold said hammers automatically in counterbalanced condition both as to static relation and centrifugal relation so that the machine will not get out of balance when being stopped, will not get into unbalanced condition when it has stopped, and will be in perfect counterbalanced condition from the instant of imparting rotative motion to the hammers of the machine whereby the strain and tension and waste of power incident to an unbalanced machine being started is avoided.

A further purpose of this invention is to provide a grinding mill of the swinging hammer type wherein the hammers of the pairs or series are all automatically held in counterbalanced condition and will remain in that condition no matter how slowly or rapidly the hammers are rotated so that I am able to provide a machine which will not only satisfactorily operate at a rapid rate of speed in rotation, but it will satisfactorily operate without waste of power, vibration, or machine strain at as slow a rate of speed as is desired or found necessary for any particular material.

A further purpose of my invention is to provide a machine wherein the hammers of a pair or set may be co-operatively connected either positively or resiliently. Where the co-operat-

ing connecting mechanism includes resilient means, the relatively backward movement of a swinging hammer when it strikes an unusual obstacle is not imparted instantly to the co-operating hammer, but the spring first yields and then the spring action draws the two swinging hammers to similar and like deflected position partly by deflecting the second hammer and perhaps partly by returning the first hammer to 10 towards normal position.

A still further purpose of this invention is to apply my aforementioned feature of automatically counterbalancing swinging hammers to types of grinding mill where the grinding may 15 be accomplished in part or wholly by crowding, pushing, or rolling the material to be broken up against the screen or breaker members, of the mill.

Further purposes and advantages of this invention will appear in the specification and claims hereinafter set forth.

While my invention is in the main illustrated and described as applied to a grinding mill where the hammers are co-operatively counterbalanced 25 in pairs, it is within the scope of my invention to so co-operatively connect a set of three or more hammers by spacing them equally about the circle and connecting them all to a common equalizer.

30 Fig. 1 is a vertical sectional view on line 1—1 of Fig. 2, illustrating one form of a grinding mill embodying this invention.

Fig. 2 is a vertical sectional view on line 2—2 of Fig. 1.

35 Fig. 3 is a side elevation of only one pair of hammers with their co-operatively connecting means as shown in Fig. 1 and the immediately adjacent part of a disk, and, in section, the shaft and two pivot rods.

40 Fig. 4 is a sectional view similar to Fig. 1 but of only the rotating parts and with all eight hammers shown and extended radially.

Fig. 5 is a diagrammatic view of the moving parts of a hammer mill as heretofore constructed 45 and in motion showing four independently swinging hammers with three in radial position and one hammer deflected or swung from radial position.

Fig. 6 is a diagrammatic view of the moving 50 parts of a hammer mill as heretofore constructed; viz, of the independently swinging hammer type and having eight swinging hammers, all swung downwardly in the position they occupy when the machine is not in operation.

55 Fig. 7 is a side elevation similar to Fig. 3 of one pair of hammers and their co-operatively connecting means illustrating a modified form of my invention.

Fig. 8 is a side elevation similar to Fig. 7 but 60 illustrating another modification of my invention and one wherein the means connecting a pair of hammers effects a resilient connection.

Fig. 9 is a side elevation of a unit of hammer-carrying links and separate hammers where the 65 links are co-operatively connected pursuant to this invention to hold the unit in counterbalanced condition.

Fig. 10 is a sectional view on line 10—10 of Fig. 9 of the parts shown in Fig. 9.

70 Fig. 11 is a view showing my invention applied to a set of three hammers.

Referring to the drawings in a more particular description, it will be seen that the grinding mill illustrated includes opposite lower housing members 10 and 11, a semi-circular perforated screen

12 supported by said housing members, an upper front breaker plate 13 at the right hand side of the machine as shown in Fig. 1 and an upper rear breaker plate 14 opposite thereto and having its upper end spaced from the upper part of the front plate 13 so as to provide the usual feed opening 15, into which the material to be operated upon is directed from the feed table or chute 16.

The semi-circular screen 12 is conveniently held in place between the lower housing members 10 and 11 by means of internal and external flanges 17 and 18 respectively which engage the inside and outside of said screen at its opposite edges. Similar or equivalent means are used to hold in place the front and rear breaker plates 15 13 and 14. The lower housing members conveniently extend down for some distance below the perforated screen thereby forming a chamber 19 for the ground material that has come through the screen. The material is taken from this chamber 19 in any of the conventional ways well understood in the art and so not requiring more definite description herein.

In suitable bearings 20 and 21 provided upon the opposite housing members 10 and 11 there is revolvably mounted the shaft 22, suitably rotated by power such as by a belt applied to the pulley 23 upon one projected end of said shaft.

In the space between the housing members there is mounted upon the shaft 22 the desired number of disks 24 and fixed to rotate with the shaft as by being keyed thereto. These disks are spaced apart conveniently by spacer rings 25 keyed to the shaft. Lock nuts 26 engage threaded portions on the shaft immediately outside of the two end or outside disks 24.

At intervals in a circle spaced out from the shaft 22 and the spacer rings 25, the disks are pierced by a plurality of pivot rods 27. These rods are parallel to the shaft and conveniently 40 extend through the whole set of disks 24. In practice, and most conveniently, the rods are arranged in pairs with the members of each pair on opposite sides of the shaft and in a direct line passing through the axis of the shaft. For 45 purpose of definiteness in description and for illustrating the machine it will be seen that the drawings show 5 disks 24 pierced by 8 pivot rods 27 and providing 4 spaces between the spaced disks, and that in each space between adjacent 50 disks are mounted on opposite pivot rods 27 two hammers. As this machine is illustrated, the hammers 28^a and 28^b are mounted in the first space counting from the right hand side of Fig. 2 on the uppermost and lowermost pivoting rods 55 27 and the two hammers 28^c and 28^d are mounted in the second space but upon the rods 27 that show in Fig. 1 farthest to the right and farthest to the left respectively. It will be understood that another pair of hammers will be 60 mounted in the third space and these must be oppositely arranged and conveniently will be arranged on two opposite rods not already carrying any hammers, and still a fourth pair of hammers will be mounted in the fourth space on 65 opposite rods and preferably upon the rods not already supporting any hammers. For the sake of clearness in the drawings, neither the third nor the fourth pair of hammers are illustrated in Figs. 1 and 2.

The hammers 28 are provided towards their inner ends with a circular hole 29 whereby the hammers are mounted upon the pivot rods 27 and may freely swing or rotate on said pivot rods. In this embodiment of my invention the inner 75

ends of the hammers are provided with spaced teeth 30 arranged in a semicircle about the center of the hole 29 and facing outwardly therefrom. That is the teeth, as appears in Figs. 1 and 3 are extended about the periphery of this end of the hammer and are conveniently formed by stamping, casting or otherwise as by cutting away the material between the teeth.

The hammers of each pair are operatively connected by an equalizer 31 which in this embodiment of my invention consists of a gear wheel having at its periphery outwardly projecting teeth 32 adapted to intermesh with the teeth 30 upon the inner ends of the hammers. This equalizer 31 is mounted upon the spacer ring 25 already described as occupying part of the space between adjacent disks 24. The periphery of the spacer ring forms the bearing upon which the equalizer 31 may freely rotate. The equalizer 20 gears 31 and hammers 28 are preferably formed slightly thinner than the spacer rings 25 and so thinner than the spaces left between adjacent disks to the end that the hammers and equalizer gear may freely rotate without binding upon the 25 adjacent disks 24. It will be understood of course that each pair of hammers is operatively connected by a spacer gear 31.

It will now be seen that each pair of hammers in this machine is separately and positively connected by an equalizer gear 31, and that this co-operative connection of the hammers of a pair will not interrupt or interfere with the usual rotation of all of the sets of hammers by the shaft 22 and the disks 24 and pivot rods 27. During 35 normal rotation of the hammers the centrifugal power will keep the hammers of a pair extended radially out from the axis of the shaft in the position of hammers 28^a and 28^b in Fig. 1. As this machine is organized the hammers rotate 40 in an anti-clockwise direction. As the lower hammer 28^b strikes an obstacle in the material to be ground the free end of said hammer will tend to swing back relatively to a radius extending through the axis of its pivot or to swing 45 to the left shown in Fig. 1. It will be obvious on account of the intermeshing of the teeth of hammer 28^b with the teeth of equalizer 31 that the said equalizer will tend to relatively rotate in an anti-clockwise direction and thereby the 50 teeth at the upper side of the equalizer being in mesh with the teeth on hammer 28^a will tend to swing said hammer 28^a in a clockwise direction relative to its pivot rod. In other words, the swinging of the free end of hammer 28^b to the 55 left will force a movement of the swinging end of hammer 28^a to the right to a similar extent. In Fig. 1 the second pair of hammers 28^c and 28^d are shown in such a deflected position, due to one hammer, say hammer 28^c having engaged 60 an obstacle that made sufficient resistance to turn back the swinging end of that hammer or more properly to hold the free end of said hammer from advancing in a radially extending line passing through the axis of the pivot rod of 65 hammer 28^c and the axis of the shaft. Due to the co-operating connection between the hammers 28^c and 28^d, hammer 28^d was relatively turned back on the axis of its pivot at the same time and to a like extent but in a reversed direction. By "reversed direction" here I mean that as the hammer 28^c was apparently swung down by the obstacle it met its companion hammer 28^d was swung upwardly. In the same way as already explained, a swinging of the hammer 70 28^b to the left would cause a swinging of ham-

mer 28^a to the right. This co-operative connection between the hammers of a pair will in effect add to the power of any hammer when it strikes an obstacle and the obstacle will have to not only relatively swing back the hammer striking the obstacle, but also will have to similarly turn back or deflect the other hammer of the pair. While the power of the hammers is thus doubled as against an obstacle the hammers can still be deflected or turned backward freely 10 enough to avoid damaging the machine.

When one hammer of a pair is turned back through meeting an obstacle, the said hammer and its co-operatively connected hammer come more or less to the position of hammers 28^c and 28^d in Fig. 1, and these deflected hammers will be in counter-balanced condition. In other words, the corresponding deflection of a pair of hammers will always insure that the hammers on opposite sides of the machine are in balanced condition both as to weight and also as to centrifugal power because a deflected hammer on one side will always have a similarly deflected hammer on the other side of the circle of the machine.

In Fig. 3 there is shown a side elevation of only one pair of hammers with their co-operatively connecting means; that is, the equalizing gear 31 and with only enough of the other parts of the machine such as the shaft 22, two pivot rods 27, 30 and a part of one of the adjacent disks 24 so as to show the automatic counterbalancing connection between this pair of hammers.

Fig. 4 is a sectional view similar to Fig. 1, showing only the rotating parts of the machine as shown in Fig. 1 but with all eight hammers shown in extended or radial position, which is the position that even my co-operatively connected hammers will assume when the machine is in operation unless one or more hammer and its 40 or their connected hammers has been deflected through an obstacle having met one hammer of any pair as hereinbefore described. This directly radiating position of all of the hammers is also the position the hammers in a machine embodying my invention would assume when the machine was stopped. In other words, when a machine embodying my invention is stopped, the counterbalanced hammers in theory and often in practice would stay all severally extended in a 45 radiating position and so the machine would be in perfectly balanced condition. If, due to slight variation in the weight of oppositely disposed hammers, the heavier hammer tipped downwardly it would turn its co-operatively connected 55 hammer upwardly to a similar extent and so the machine would be in balance when it was again started. The counterbalanced situation of my hammers either as shown in Fig. 1 or Fig. 4 is in marked contrast to the badly unbalanced condition the independently mounted hammers of former machines have assumed when machine was stopped.

Figure 6 is a diagrammatic view of the moving parts of a hammer mill of the independently 65 swinging hammer type as heretofore made when the machine is stopped. In the machine shown in Fig. 6 the hammers 33 are independently swingingly mounted at their inner ends upon pivot rods 34 projecting through a series of disks 70 35 which are fixed upon the rotated shaft 36. In other words, the machine shown in Fig. 6 is in general construction like my machine shown in Figs. 1, 2, 3, and 4 except that the machine shown in Fig. 6 has no means co-operatively connecting 75

and counterbalancing the pairs or sets of hammers. It will be seen from inspection of Fig. 6 that due to the dropping of all of the hammers of the machine to as nearly a straight downward position as possible the machine there shown will be badly unbalanced each time it is stopped and will remain badly unbalanced for a considerable time after the machine is started. One of the main objects of my invention is to overcome this greatly unbalanced condition of swinging hammers when the machine is first started.

In Fig. 5 there is shown a diagrammatic representation of a hammer mill having disks 35^a, pivot rods 34^a and four independently swinging hammers 33^a where one hammer has been deflected due to striking an obstacle. It will be seen that the machine illustrated in this view is out of balance due to having much more weight and centrifugal tension on one side of a diagonal line than the other, and that this machine will remain out of balance until the centrifugal power gradually draws the deflected hammer outwardly. This condition is in marked contrast to the counterbalanced condition of the four hammers shown in my machine in Fig. 1 where a deflection of one hammer has turned its oppositely disposed and co-operating hammer to a counterbalanced position. It will be understood of course that after my machine has had some of its hammers come to a deflected position as shown in Fig. 1 these deflected hammers will return to normal radiating position due to the centrifugal action of the rapidly rotating parts, but during all the interval of the deflected hammers returning to normal directly radiating position the said unit of the machine or the co-operating pairs of hammers and the machine as a whole will be in counterbalanced position because the two deflected co-operatively connected hammers will in all positions of the said connected hammers be in counterbalanced position due to the said hammers being operatively connected to cause equal motion of the said hammers both on the deflection and on the return from deflection.

Fig. 7 is a side elevation of a unit of a machine embodying my invention in a modified form. In this modified form, instead of several teeth and intervening notches on both the equalizer and the inner end of the hammers, there is provided only one tooth or projection and one indentation or notch on the corresponding intermeshing parts. In this form of my machine the shaft 31, spacer ring 38, spaced disks 39 and the pivoting rods 40 are all the same as the corresponding parts shown in Figs. 1 to 4, but in the machine of Fig. 7 the inner ends of the hammers 41 are provided with laterally projecting bosses 42 preferably circular in side elevation, and the stabilizer 43 is provided with two oppositely disposed inwardly extending U-shaped recesses or notches 44, adapted to swingingly receive the bosses 42 of hammers 41. In this construction the hammers 41 and the stabilizer 43 overlap, allowing the laterally projecting bosses 42 to project into the U-shaped recesses 44. It will be understood that the notches 44 are deep enough to allow a considerable swinging of the hammers 41 on their pivot rods 40 and in fact to allow as much swinging action as the hammers will ever be called upon to make without the bosses becoming disengaged from the recesses 44. It will be seen that in effect this intermeshing of the bosses upon the hammers with the stabilizer is a mechanical equivalent of the full set

of teeth on the equalizer gear 31, and the semi-circular sets of teeth 38 upon the hammers 28. In this modification also the hammers of a set will at all times be held in counterbalanced condition automatically.

Fig. 8 shows a further modification of my invention in that in this construction the means co-operatively connecting the oppositely disposed hammers 45 include resilient means whereby a forced deflection of one hammer is not instantaneously and fully transmitted to the other hammer, but a yielding connection is provided which absorbs part of the shock of the deflection of the first hammer, and then gradually transmits the deflection to the other hammer. In the form of this resilient connection shown in Fig. 8 the equalizer 46 has secured to its outer periphery two oppositely disposed bow-shaped springs 47. The circle of each bow fits a portion of the equalizer 46 and is secured thereto by screws 48. The projected ends 47^a of these spring members are spaced apart on each side of the machine sufficiently to receive therebetween the ears 49 provided upon the inner ends of the hammers 45. In this construction it will be understood of course that the hammers 45 are swingingly mounted near their inner ends upon pivot rods 50 projecting through two or more of the rotated disks 51, said disks being mounted upon the shaft 52 and rotated thereby as by a proper key. In this construction also preferably I used the spacer rings 53 to hold the disks apart and to provide a bearing for the equalizer 46. Assuming that the left hand hammer of this Fig. 8 strikes an obstacle which deflects said hammer upwardly the ear 49 of this hammer will travel downward relative to the pivot rod 50 carrying said hammer and will exert its power in the first place upon the left hand projecting end 47^a of the lower spring 47. The construction of said spring 47 is such as to allow the left hand arm or end 47^a to bend slightly, thus somewhat cushioning the positive action of the ear 49 of the left hand hammer 45. The spring action, however, of this left hand end of the lower spring 47 will at once tend to rotate the equalizer in an anti-clockwise direction. This tendency to rotate will be partly absorbed by the bending under spring action of the right hand arm 47^a of the lower spring 47 coming into engagement with the ear 49 upon the right hand hammer 45. The directly upward rotation of the right hand arm 47^a of the lower spring 47 would of course tend to swing the outer end of right hand hammer 45 downwardly against the centrifugal action of said hammer 45. It will thus be seen that the spring action or resilient means provided in this construction ultimately moves the connected hammer to counterbalancing position and will thereafter hold the hammer in counterbalanced condition until they gradually but concurrently come back to normal radiating position.

Referring to the modification illustrated in Figs. 9 and 10, it will be seen that the fixed parts of the machine are the same as illustrated in Figs. 1, 2 and 3 and already described in detail and that the shaft 54, the spacer rings 55 and toothed equalizers 56 are the same as the corresponding parts 22, 25 and 31 in the machine shown in Figs. 1, 2 and 3. The hammers in this modification however differ from those first described in connection with Figs. 1 to 3 and also from any of the hammers shown in the other figures of the drawings in that in this modification instead of integral one-piece hammers there

are used two-piece hammers or hammer assemblies consisting of the hammer link 57 and an extra part or separate hammer end either in the form of a disk 58 or an irregular or angular shaped hammer end 59. The hammer links 57 are provided with holes 60 near their inner ends whereby the hammer links and thereby each separate hammer assembly is pivotally mounted upon its pivot rod 61 which pivot rods in turn are carried as heretofore described with other forms of the machine by the plurality of large disks 62. The periphery of the inner end of each hammer link 57 is provided with radially arranged teeth 63 intermeshing with similarly arranged teeth 64 upon the equalizers 56 so that when either hammer link 57 of the pair of such links co-operatively connected to one equalizer 56 is deflected the other hammer link of the pair will be correspondingly deflected, resulting in the cooperative connection and the counterbalanced result heretofore described in detail with other forms of my machine. The separate hammer disk 58 or hammer ends 59 are pivotally mounted upon their respective hammer links 57 as by said members 58 or 59 being provided with a hole therethrough rotatively fitting a pivot pin or bolt 65. As these members whether disks or angular ends are pivotally mounted upon the outer ends of the hammer links 57, it will be seen that they will rotate more or less closely to the screen 12 and will have considerable of a rolling and pushing or pressing action upon the material being handled by the material. It will be obvious that these separate hammer ends may be all disks 58 or all angular shaped ends as the parts 59 or that other more irregular shaped separate hammer ends may be used or any combination thereof. It is obvious from the illustration and explanation already made that each pair of hammer assemblies operatively connected by a toothed equalizer 56 will always be in counterbalanced position not only when the hammer assemblies are extended radially in normal running position, but when any one of the hammer assemblies has been deflected by meeting an obstacle or by having come to other than a direct radiating position due to the stopping of the machine as heretofore mentioned.

Fig. 11 is a detailed view similar to Fig. 3 but illustrating a further modification of that form of my machine wherein instead of simply a pair of hammers there is used a set of three hammers 66. These hammers are co-operatively connected together through all of them intermeshing with the equalizer 67 rotatably mounted upon the ring 68 carried on the main shaft 69. All of the hammers 66 of this set of three are of course carried in the space between two adjoining hammer-carrying disks 70 and are pivotally mounted on three rods 71 which are equally spaced about the circle and of course are spaced an equal distance out from the axis of the shaft 69. This modification illustrates the feature that my invention is not limited to co-operatively connecting simply a pair of hammers in counterbalanced condition but may be used to hold a set of three or more hammers in such situation. As long as these hammers are mounted on pivot rods equally spaced apart, the hammers will be in balanced situation as to direct weight and also as to centrifugal tension in any condition of the machine.

What I claim as new and desire to secure by Letters Patent is:

1. In a grinding mill, the combination of a set of rotated hammer-carriers, including pairs of oppositely disposed pivots spaced out from the axis of said carriers, hammers respectively mounted near their inner ends on said pivots and means including resilient members co-operatively connecting the hammers of each pair for like movement on their pivots whereby on swinging motion of either hammer on its pivot a like swinging motion is imparted to the other hammer of the pair.

2. In a grinding mill, the combination of a set of rotated hammer-carriers, including pairs of oppositely disposed pivots spaced equally from the axis of said carriers, hammers respectively mounted near their inner ends on said pivots and having projections at their inner ends and for each pair of hammers a separate equalizer revolvably mounted on the axis of said hammer carriers having at its opposite sides arms having a resilient action and intermeshingly engaging the said projections of a pair of hammers whereby said pair of hammers are co-operatively connected with a resilient action for like movement on their pivots.

3. In a grinding mill, the combination of rotated hammer-carriers, including a series of pivots equally spaced out from the axis of said carriers and equally spaced from one another, hammers respectively mounted near their inner ends in sets on said pivots and means including resilient members co-operatively connecting the hammers of each set for like movement on their pivots whereby on swinging motion of any hammer on its pivot a like swinging motion is imparted to the other hammer or hammers of said set.

4. In a grinding mill, the combination of a plurality of rotated hammer-carriers, including pairs of oppositely disposed pivots spaced equally from the axis of said carriers, hammers arranged in independent pairs and respectively mounted near their inner ends on said pivots and having projections at their inner ends and for each pair of hammers a separate equalizer revolvably mounted on the axis of said hammer carriers and interengaging at its opposite sides said projections at the inner ends of its pair of hammers whereby all the hammers connected to an equalizer are co-operatively connected for automatic counterbalanced like movement on their pivots and independent of any movement of the hammers of other pairs.

5. In a grinding mill, the combination of rotated hammer-carriers, including a series of sets of pivots equally spaced out from the axis of said carriers and equally spaced from one another, hammers respectively mounted near their inner ends in separate sets on said pivots and having projections at their inner ends and means including a separate equalizer for each set of hammers revolvably mounted on the axis of said hammer carriers and having parts intermeshingly engaging the inner ends of the hammers of that set for co-operatively connecting the hammers of that set for like movement on their pivots when one hammer of the set is moved whereby all the hammers of the respective sets are held in counterbalanced position when the mill is operating at any speed and when the mill is not operating.

JOHN MURSCH.
